UNITED STATES PATENT OFFICE.

ARTHUR ELPHINSTONE CUMMINS, OF 118 HAVERSTOCK HILL, COUNTY OF MIDDLESEX, ENGLAND.

BALE-PRESS.

SPECIFICATION forming part of Letters Patent No. 429,188, dated June 3, 1890.

Application filed July 31, 1889. Serial No. 319,299. (No model.) Patented in England March 12, 1888, No. 3,805.

To all whom it may concern:

Be it known that I, ARTHUR ELPHINSTONE CUMMINS, engineer, a subject of the Queen of Great Britain, residing at 118 Haverstock Hill, in the county of Middlesex, England, have invented certain new and useful Improvements in Apparatus for Compressing Cotton or other Materials into Bales, (for which I have received Letters Patent in Great Britain, No. 3,805, dated March 12, 1888,) of which the following is a specification.

In the specification of a former patent granted to me in Great Britain, No. 1,005, in the year 1885, I described a press in which two, three, or more filling-boxes were used for delivering material into a bale-chamber to make up a bale, and the bale-chamber was provided with grids or movable fingers which retained the material in the bale-chamber when it had once been delivered into it. The bale-chamber was carried at the end of a swinging arm and brought first over one filling-box to have material discharged into it from this box, then brought over another box, and so on.

According to my present invention I construct the press in such manner that the bale-chamber, after having the contents of two or more feeding-boxes delivered into it, can be brought over the top of the ram of a powerful hydraulic cylinder, so that the material may be finally compressed in this bale-chamber. I also construct the press without framing for taking any of the strains arising from the pressing of the material, so that the cost of the press is much reduced and greater freedom in working it obtained. The several filling-boxes, with their hydraulic rams and the hydraulic cylinder for giving the final compression, I range in a circle, all independent one of the other. They may be buried in the ground or otherwise held in place by suitable supports. The horizontal arm which carries the bale-chamber I support upon balls or rollers which rest upon a circular bed, so that the bale-chamber may readily be moved round in a circular path. When the bale-chamber has been brought over the top of the hydraulic cylinder, I lock it to this cylinder by locking mechanism sufficiently strong to withstand the strain that will be brought upon it

when the ram of the cylinder is giving the final compression to the bale of material in the chamber. Preferably I form the top of the cylinder with an outwardly-projecting flange and embrace it with a loose ring which has an inwardly-projecting flange at the bottom. The upper part of the ring I form with an internal parallel thread around it cut away in vertical segments. The exterior of the bottom of the bale-chamber I make circular and with corresponding threaded segments on its exterior. To lock the bale-chamber to the cylinder, the ring is lifted upward until the projecting segments of the ring have passed into the spaces between the projecting segments on the chamber. A partial turn is then given to the ring to cause the threaded segments upon it to lock with the threaded segments on the chamber. The locking may also be performed without using threaded segments. Projecting segments engaging each other on a partial twist may be used. In this way the strains caused in compressing the material are carried by the sides of the cotton-boxes and bale chambers and cylinders, and hence the need of using framework to take these strains is done away with. The ring is supported by a lever carrying a counterbalance-weight, so that the ring (the weight of which would be considerable) can readily be raised and lowered.

The same means may be employed for locking the bale-chamber to the filling-boxes, or other ready means may be provided for locking it to these boxes, as the strains which will come upon them will be comparatively light.

One, two, or more bale-chambers revolving independently or in conjunction with one another and one or two or more sets of filling-boxes may be used with one or more hydraulic cylinders for giving the final compression.

It is not essential that the filling-boxes and hydraulic cylinder should be ranged in a circle. They might, if preferred, be ranged in any other curve or in a straight line.

Figure 1 is a horizontal section, and Fig. 2 a side elevation, partly in section, of baling apparatus constructed as above described. Fig. 3 is an end view of one of the bale-chambers; Fig. 4, a horizontal section on the line 100

1 2; Fig. 5, a horizontal section on the line 3 4, and Fig. 6 a vertical section of one of the bale-chambers with the side doors open. Fig. 7 is an end elevation, partly in section, of the mechanism for locking the bale-chamber to the filling-boxes. The gearing is only shown applied to one filling-box, but similar gearing is applied to each box. Fig. 8 is a vertical section; Fig. 9, a cross-section of a modified construction of the press adapted for light baling. Figs. 10, 11, 12, and 13 show various views, on a larger scale, of the locking-bolts by which the bale-chambers are held to the top of the filling-boxes and the mechanism by which the bolts are actuated. Fig. 10 is a side elevation, and Fig. 11 a plan with the parts in the position they assume when the bolts are unlocked. Fig. 12 is a front elevation with part of the frame in section, showing one of the bolts in its locked position; and Fig. 13 is a section through the line *a b* of Fig. 12. Fig. 14 is an end elevation of one of the vertical ends of one of the bale-chambers and the bolts carried by it. Fig. 15 is a horizontal section of the bale-chamber, taken on the level of the line *c d* of Fig. 14, and Fig. 16 a horizontal section of the bale-chamber on the level of the line *e f*, Fig. 14. Fig. 17 is a plan view of the locking-ring; Fig. 18, an end elevation of the lower part of one of the bale-chambers with the locking-ring in section below and disengaged from it, and Fig. 19 a horizontal section through the lower part of one of the bale-chambers. Fig. 20 shows in section a modified construction of the central post around which the bale-chambers turn.

In Figs. 1 to 7, A B C are three filling-boxes, each fitted with a movable bottom, which can be pressed upward by the ram of a hydraulic press X. D is the hydraulic press for finally compressing the bales. E E are two bale-chambers, the bottom portions of which are carried by arms F' from rings F, which can swivel around the fixed cylindrical post G. H H are ball-bearings for the rings to run on. This post might, if preferred, be arranged underneath the floor-level, and the swiveling arms be made to revolve inside it, as is illustrated in the vertical section, Fig. 20.

When a bale-chamber is to be attached to one or other of the filling-boxes, it is brought over the top of the box, and two T-headed catches H^x, which are jointed to the top of the box, are turned upward and inward and their T-heads made to come above projections *h* from the exterior of the bale-chamber, and so hold it down, as shown in detail at Fig. 12.

In order to be able to turn the catches H^x into position to lock the bale-chamber or to unlock it, each catch H^x has a bevel-pinion H' upon its axis, into which gears a corresponding pinion I' on inclined axes I. (See Figs. 2, 7, 10, 11, 12, and 13.) These axes are geared by other bevel-pinions *i* and *j* with a horizontal axis J, which can be turned whenever desired by turning an axis J' by a lever-

arm J^x, which extends from it, the axis J' having upon it a beveled toothed arc *j*, gearing into one of the bevel-pinions on the axis J, or these catches may be worked in any other suitable manner.

As shown in Figs. 2, 4, and 5, the bottom part of each bale-chamber has a parallel thread around it cut away in segments. 75

To attach the bale-chamber to the top of the cylinder of the hydraulic press D, this cylinder has around it at the top an outwardly-projecting flange D, (see Fig. 2,) and is embraced by a ring K, within which are segments of parallel thread, which project from the bottom of the bale-chamber, or plain segments without thread might be used. (See Fig. 18.) When the bale-chamber has been brought over the cylinder of the press, the ring is raised until an inwardly-projecting flange around its lower end comes against the flange which is around the top of the cylinder. A partial turn is then given to the ring to cause its segments to engage with the segments on the bale-chamber. The ring is turned by handles K', which stand out from it, or in other suitable way, the power necessary being very small. In order to be able to readily raise the ring whenever it is required to do so, the ring is supported on one end of lever-arms L, (see Figs. 1 and 2,) which at their opposite ends have weights L' hung onto them nearly to balance the weight of the ring. The ring being thus approximately balanced, it can readily be raised by a man putting his foot on a treadle M and putting increased weight on the weight end of the lever-arms.

Each bale-chamber is at the bottom formed with a series of parallel slots through two of its opposite sides for the grid-fingers N, (see Fig. 6,) which are to retain material in the bale-chamber. The grid-fingers are segments of disks, and each set of grid-fingers is carried by an axis O, as in bale-chambers heretofore made by me.

The bale-chambers themselves may be constructed in any suitable manner. In the construction shown in the drawings the lower portion of the bale-chamber is fixed to one of the arms F'. Two opposite sides of the chamber are at the bottom jointed by horizontal hinge-joints *e* to the lower portion. At the top they are drawn together by turning a screw-spindle O^x, which has right and left handed screw-threads upon it working in gun-metal nuts fitted in pockets cast in the sides, and the sides hold between them the top P of the chamber. The other two sides are jointed by vertical hinge-joints Q to one of the sides, and can be turned around vertical axes Q, and can be locked in their closed position by bolts R, as best seen in Figs. 4 and 14. When the doors are closed, the bolts R are slid endwise to lock them by eccentrics on the pins Q of the hinge-joints. In order to be able to turn the pins Q, each pin has upon it a worm-wheel S, into which

gears a worm T on a spindle U, which can be turned by a hand-wheel V upon it. As before stated, the bale-chambers might be made to run upon a straight or curved track to bring them first over the filling-boxes and then over the finishing hydraulic cylinder; but I prefer to mount them upon arms which swivel around or inside of a central post, as above described.

10 In the modified construction of press shown at Figs. 8 and 9, A B are two filling-boxes, each fitted with a movable bottom, which can be pressed upward by the ram of a hydraulic cylinder, as in the press above described. C is a third filling-box fitted with a movable bottom, which can be pressed upward by a ram X of larger diameter than the rams used with the boxes A and B. E is a bale-chamber which can swivel around the central post G. On the outer side the box is supported on small wheels x, which run on the top of the fixed bed-plate Y. H^x are T-headed catches jointed to the frame which carries the filling-boxes. By these catches the bale-chamber can be locked above either of the filling-boxes. The catches H^x hold down the bale-chamber just in the same way as the catches H^x shown in Figs. 10, 11, 12, and 13; but in place of their being turned by gearing, as shown in those figures, they can be turned by hand either into a vertical position to lock the bale-chamber and hold it down or be turned downward to release it. The bale-chamber is also prevented from rising by the head of the post G. 35 The bale-chamber itself may be constructed in the manner hereinbefore described, or in other suitable manner.

What I claim is—

1. The combination of a hydraulic cylinder, a filling-box fixed at the bottom to the top of the hydraulic cylinder, the movable bottom of the filling-box constructed to be pressed upward by the ram of the hydraulic cylinder, a bale-chamber adapted to be brought over the filling-box, grid-fingers for preventing the

return of material fed into the bale-chamber, and catches to lock the bottom of the bale-chamber to the top of the filling-box.

2. The combination of two or more filling-boxes, each fixed at the bottom to the top of a hydraulic cylinder and arranged in a circle, a pivot-post at the center of the circle, a bale-chamber carried by an arm which can turn around the post, grid-fingers which prevent the return of material fed into the bale-chamber, and catches to lock the bottom of the bale-chamber directly to the top of either of the filling-boxes.

3. The combination of two or more filling-boxes, each fixed at the bottom to the top of a hydraulic cylinder arranged in the arc of a circle, a hydraulic cylinder in the same circle on the opposite side of the center, a pivot-post at the center, a bale-chamber carried by an arm which can turn around the pivot-post, grid-fingers which prevent the return of material fed into the bale-chamber, and devices for locking the bottom of the bale-chamber directly to the top of either of the filling-boxes or to the hydraulic cylinder.

4. The combination of two or more filling-boxes, each fixed at the bottom to the top of a hydraulic cylinder arranged in the arc of a circle, a hydraulic cylinder in the same circle on the opposite side of the center, a pivot-post at the center, two or more bale-chambers, each carried by an arm that can be turned around the post and independently one of the other, grid-fingers which prevent the return of material fed into the bale-chambers, and catches to lock the bottom of the bale-chambers directly to the top of either of the filling-boxes.
